UNITED STATES PATENT OFFICE.

LOUISA P. BUNNELL AND WILLIAM NICHOLS, OF TOLEDO, OHIO.

SELF-THREADING NEEDLE.

SPECIFICATION forming part of Letters Patent No. 643,398, dated February 13, 1900.

Application filed January 10, 1899. Serial No. 701,711. (No model.)

To all whom it may concern:

Be it known that we, LOUISA P. BUNNELL and WILLIAM NICHOLS, citizens of the United States, residing at Toledo, Lucas county, Ohio, 5 have invented certain new and useful Improvements in Self-Threading Needles, of which the following is a specification.

There have been numerous attempts to construct sewing-machine needles in such form 10 that they may be threaded by passing the thread into the eye laterally through a transverse opening provided for that purpose, but such devices have not proved satisfactory and have failed to come into public use for 15 various reasons, the chief of which is that the outer edges of the lateral opening have caught in the fabric as the needle passes into and out of the goods, thus marring the fabric; also, that the thread does not remain in the eye of 20 the needle, but at times slips out through the opening, causing annoyance and delay.

Our invention relates to and its object is to provide means for overcoming the difficulties here indicated and to furnish a needle which 25 may be threaded without passing the end of the thread into the eye of the needle, also to provide a needle which may be instantly threaded, even in the dark, and which will not injure the threads of the fabric upon 30 which it is used and which will hold its thread in such manner that it cannot slip out of the eye of the needle. We accomplish these results by means of the device hereinafter described, and shown and illustrated in the single figure of the accompanying drawing, made 35 part hereof, which represents a needle of exaggerated size constructed according to our invention.

In the drawing, *a* is the shank, *b* the shaft, 40 and *c* the eye, of the needle.

d is a transverse cut or opening at a right angle to the axis of the needle, leading from the side of the needle into the eye *c*. The cut *d* leads to and coincides with the end of the 45 eye next the point and at its inner end is

barely of sufficient width vertically to permit the passage of the coarsest thread designed to be used with the needle.

What we mean by the cut being at a right angle to the axis and coinciding with the bottom of the eye is that said cut extends beyond the longitudinal axis of the needle to the opposite wall of the said eye. 50

The cut *d* at its outer end is somewhat flaring and its edges are rounded slightly, as 55 shown, so that when the needle passes into and out of the fabric there will be no rough corner to catch the goods. The thread when passed laterally into the cut is guided by the flaring opening into the eye. As the thread 60 on one side of the needle always leads upwardly, it is not at any time permitted to slip into the narrow outlet of the cut.

The operation of our device is as follows: The thread is pressed laterally into the flaring mouth of the cut *d* and slides into the eye 65 of the needle sidewise at the extreme bottom end of the eye. The normal position of the thread in the sewing-machine now pulls the thread above the cut *d*, so that the thread cannot escape through the cut. It will be seen 70 that the rounded corners of the mouth of the cut prevent the threads of the fabric from being cut or torn and from finding their way into the cut when the needle is in operation. 75

Having described our invention, what we claim, and desire to secure by Letters Patent, is—

The needle herein described, the same having a cut at a right angle to the axis thereof 80 and coinciding with the bottom of the eye, said cut having a flaring mouth with upper and lower rounded corners, substantially as and for the purpose specified.

LOUISA P. BUNNELL.
WILLIAM NICHOLS.
